[57] CLAIM

The ornamental design for a tool and solder station, as shown and described.

DESCRIPTION

FIG. 1 is a front and top perspective view of the tool and solder station, showing one form of my new design; FIG. 2 is a rear, top and left side perspective view of the tool and solder station shown in FIG. 1;

FIG. 3 is a back, bottom and left side perspective view of the tool and solder station shown in FIG. 1;

FIG. 4 is a view similar to FIG. 2 of a modification, which is identical to the embodiment illustrated in FIGS. 1-3 except for the wire holder, added in the upper left corner, for receiving a soldering iron.

The not shown right side of the principal embodiment and the modification is flat and unornamented.
